UNITED STATES PATENT OFFICE.

GEORGE R. LUM, OF NEW YORK, N. Y., ASSIGNOR TO WESTERN ELECTRIC COMPANY, INCORPORATED, OF NEW YORK, N. Y., A CORPORATION OF NEW YORK.

CONTACT-SPRING VIBRATION DAMPER.

Application filed December 13, 1920. Serial No. 430,405.

This invention relates to the use of vibration absorbent means in connection with electrical contact springs for prevention of vibration of said springs as they are brought into and out of contact with contact blocks cooperable therewith.

The object of this invention is to provide means for effectively preventing the vibration of electrical contact springs upon being brought into and out of contact with contact means of varying height.

In adjustable electric circuits wherein the adjustment is controlled by the making or breaking of contacts usually between spring contact members and contact blocks, it is inevitable that certain inequalities in level of the successive contacting surfaces must exist. In passing over these inequalities, if the contact is a laterally sliding one or, in making or breaking contact if the motion is one of frontal advance or receding, the contact springs normally are subjected to vibration of an amount dependent on the degree of inequality in successive surfaces encountered, the nature of the contact material, and the stiffness of the springs. Wherever contacts are made and broken rapidly in a circuit containing a sensitive recording device such as an oscillograph, cathode ray tube, or telephone receiver held at the ear, for determinations of comparative performances of apparatus, the vibration of the contact springs used in the adjustment mechanism produces an oscillating effect in the minute are formed on breaking the circuit and in the arc that occasionally accompanies the circuit closure. This oscillation in the arc produces an uneven line in the visual field of an oscillograph and cathode ray tube or a singing effect in the receiver. These effects are disturbing and, if their recurrence is rapid, make the resultant visual or oral effects sought unintelligible.

To obviate the difficulties above set forth, this invention provides means which may consist of felt or similar vibration absorbent material so situated adjacent contact springs as to prevent or greatly minimize their vibration upon being subjected to inequalities in surfaces contacting with them.

It is appreciated that use of means for damping vibration of strings in musical instruments is old in the art and such a combination is not contemplated in this invention but the damping means is here applied

to electrical contact springs to facilitate a prompt and complete make or break of circuit as the case may be without oscillation in the arc that may be produced.

The illustrative drawings disclose the damping means of this invention as applied to an electrical compensator switch such as may be used to electrically control compensation of time phase difference in electrical impulses transmitted over a plurality of circuits. It is to be understood that drawings show but one application of this invention and do not define the limits thereof, reference being directed to the appended claims for this purpose.

Fig. 1 discloses a vertical cross sectional view of an electrical time phase compensator switch with fixed contact springs and rotary connector blocks cooperable therewith. The spring damping means of this invention is shown in contact with each spring.

Fig. 2 discloses an enlarged view of a section of the fixed portion of a compensator switch showing springs mounted thereon and vibration dampers in proper position.

Fig. 3 discloses a telephonic transmitter circuit for detection of sound vibrations and their conversion into electrical impulses, said circuit electromagnetically coupled through an electrical time phase compensator having contact springs and slid able connector blocks cooperative therewith, to a telephone receiver.

In detail, referring to Fig. 1, there is disclosed a composite mounting of insulating material composed of a disk 1 and ring 2, contact springs 3 and 4 with bent-up ends 5 and 6, said ends being so adjusted as to bring a plane joining them parallel to the mounting plate 1. An insulating plate 7 on which are mounted connector blocks 8, said blocks being cooperable with contact springs 3 and 4, is retained in a plane parallel to spring mounting plate 1 by a stud shaft 9, and said insulating plate 7 is rotatable by means of a hand wheel 10. Pads of resilient insulating material which may consist of felt or soft rubber, are disclosed in contact with the contact spring 3 and mounting 1; also between springs 3 and 4 and in contact with them and the insulating ring 2, said pads for the purpose of eliminating spring vibration when encountering inequalities in the contact sur-

face of connector blocks 8 or from these connector blocks into the spaces therebetween.

In detail referring to Fig. 2, there is disclosed a part of the same structure as described in connection with Fig. 1 but enlarged so as to clearly show that the resilient insulating pads 11 and 12 substantially fill the spaces between adjacent springs 10 and the composite insulating mounting 1, 2.

In detail, Fig. 3 discloses a telephonic transmitter 13 connected in series with a source of electrical energy 14 and the primary 15 of an induction coil, said circuit 15 for the purpose of converting sound vibrations received by said transmitter into the corresponding electrical impulses. The secondary 16 of said induction coil is connected through an electrical time phase 20 compensator consisting of series inductance 17 and shunt capacity 18 and switching means consisting of an insulating plate 7 and connector blocks 8 cooperating with contact springs 3 and 4 to adjust the amount 25 of said compensator in circuit with a telephonic receiver 19. The main purpose of the disclosure of Fig. 3 is to illustrate how

vibration of the contact springs 3 and 4 would occur without the presence of the vibration damping means of this invention. 30 A secondary purpose is to show where a switching means of the type described above may be used.

What I claim is:

In an electrical switching mechanism, the 35 combination of a plurality of sets of flat contact springs each set comprising springs bent up at one end and arranged in a radial line and having their bent up ends in the same plane, a composite mounting of insulating material therefor, connecting blocks engageable with the bent up ends of said sets of springs and attached to a rotatable insulating plate, and resilient insulating pads 40 triangular in shape in contact with the lower faces of the springs of each set and with said mounting and approximately filling the space between springs of each set and said mounting.

In witness whereof, I hereunto subscribe my name this 9th day of December 50 A. D., 1920.

GEORGE R. LUM.
